PUMP DEVICE

Werner F. Schultz, Flint, Mich., assignor to General Motors Corporation, Detroit, Mich., a corporation of Delaware

Filed June 11, 1962, Ser. No. 201,616
10 Claims. (Cl. 103—87)

This invention relates to a compact assembly of parts of combined electric-fluid motor means and, more particularly, to an electric fuel pump unit.

An object of this invention is to provide a new and improved structural arrangement of motor-pump components easy to assemble into a compact unit without need for screw fasteners, yet having proper alignment and concentricity between stator and rotor parts with a minimum of electrical circuitry.

Another object of this invention is to provide an electric fuel pump assembly including a centrifugal pump portion and electric motor portion which share a rotating part supported and located by a single bearing means in a unitary body portion disposed toward one end of a suitable shaft of the rotating part and having a sheet metal cover carrying an electrical stator axially mountable to one side of the unitary body portion, the unitary body portion being a central part to which all other parts are assembled.

Another object of this invention is to provide an electric motor stator portion for use with an electric fuel pump assembly including a centrifugal pump portion on one side of a unitary angular body portion notched along one side thereof to complement a cup-like cover or substantially cylindrical case portion into which permanent magnet sealed means can be press-fitted to have correct alignment axially of a single bearing means located in the unitary body portion onto which the cover or case portion interlocks with a snap fit of at least one inward projection thereof against the unitary body portion where notched, there being a single shaft journaled by the single bearing means and supporting a pump impeller on one end thereof as well as wound motor rotor means on an opposite end thereof.

A further object of this invention to provide an electric fuel pump actuated by a direct current motor having a single bearing means for rotor support with a concentric commutator means fastened directly to an armature core and located circumferentially to the bearing means to result in optimum conditions of concentricity maintained as to a unitary body portion to which all other parts are assembled including pivotally mounted brush means to engage the concentric commutator means on a side of the body portion opposite to a side where a centrifugal pump portion with impeller is located.

Another object of this invention is to provide an electric fuel pump actuated by a direct current motor having a bearing means for wound rotor-commutator support and a concentrically mounted stationary field means on one side of a unitary body portion having a centrifugal pump portion with impeller on an opposite side thereof, a brush assembly also carried by the unitary body portion and including arm-like insulating means pivotally retained therewith by ring means without requiring separate brush rigging and having brushes on pairs of arm-like insulating means to which a cable and sheath thereof are connected respectively, each arm-like insulating means having a pivot projection at an end thereof remote from the brush carried thereby and located in a recess also provided in the unitary body portion.

Another object of this invention is to provide an electric fuel pump actuated by a direct current motor having a unitary base part of moldable plastic material centrally to receive bearing means for rotor-commutator shaft sup-

2

port and a concentrically mounted stationary field means on one side thereof as well as a centrifugal pump portion with impeller on an opposite side thereof, a brush assembly also carried by the unitary base part and including a brush means without pigtail though each with a holder thereof of strip-like metal having an indented generally L-shaped pivot end that engages a metal support strip one end of which has a connector pin means to hold the support strip to the unitary base and to project therethrough for direct external electrical connection thereto, the pivot end of the metal brush holder having direct engagement against an elbow-like end of the support strip while a substantially U-looped or modified elliptical spring means straddles the elbow-like end of the support strip and the indented generally L-shaped pivot end of the metal brush holder biased radially inwardly thereby to urge engagement of the brush means against the commutator.

Further objects and advantages of the present invention will be apparent from the following description, reference being had to the accompanying drawings wherein preferred embodiments of the present invention are clearly shown.

In the drawings:

FIGURE 1 is a top end view of an electric fuel pump assembly in accordance with the present invention.

FIGURE 2 is an elevational cross-sectioned view taken along line 2—2 in FIGURE 1.

FIGURE 3 is a view taken of unitary body portion in the direction of arrow 3 in the assembly of FIGURE 2.

FIGURE 4 is a cross-sectional view taken along line 4—4 in FIGURE 3.

FIGURE 5 is a cross-sectional view taken along line 5—5 in FIGURE 3.

FIGURE 6 is a plan view of the unitary body portion as seen from the electric motor side thereof.

FIGURE 7 is a side view of shaft-mounted wound rotor-commutator means for use in the electric fuel pump assembly in accordance with the present invention.

FIGURE 8 is an end view of the rotor-commutator means taken in the direction of arrow 8 in FIGURE 7.

FIGURE 9 is a diagrammatic illustration of interconnection of the wound rotor-commutator means of FIGURES 7 and 8.

FIGURE 10 is a plan view of pump impeller means for use in the electric fuel pump assembly having an end plate outlined therewith.

FIGURE 11 is a plan view to illustrate screen and pump inlet ports on the electric fuel pump assembly in accordance with the present invention.

FIGURE 12 is a plan view of a pad-like base support ring to fit circumferentially around the unitary body portion of the electric fuel pump assembly in accordance with the present invention.

FIGURE 13 is a fragmentary side view of the support ring of FIGURE 12.

FIGURE 14 is an end view of a subassembly of stator field means and a cylindrical cover or case portion for use with the electric fuel pump assembly in accordance with the present invention.

FIGURE 15 is a partially sectioned side view of the subassembly of FIGURE 4.

FIGURE 16 is a plan view of brush and arm-like insulating support means therewith as well as sheath-cable connection thereto in accordance with the present invention.

FIGURE 17 is a sectional view of modified electric fuel pump assembly taken through line 17—17 in FIGURE 18 further in accordance with the present invention.

FIGURE 18 is a cross-sectional view taken along line 18—18 in FIGURE 17.

FIGURE 19 is a side view of the brush assembly per se taken in the direction of arrow 19 in FIGURE 18.

There is continued emphasis on improvement of components for increased durability and reliability while facilitating production at reduced costs and increasing compactness of such components including, particularly, electric motor features feasible for driving an electric fuel pump means as well as a fan, blower, or other types of impeller or pump means where close coupling of the motor and the load is desirable. The drawings illustrate improved structural arrangement of combined electric-fluid motor means generally indicated by numeral 20. This combined electric-fluid motor means 20 can include a base or unitary body portion 21 generally annular in shape as apparent in FIGURE 1 as well as in FIGURE 3 and FIGURE 6. This base or unitary body portion can be made as a metal die casting or molding or other suitable material having an integral upwardly extending annular projection 22 with a passage therethrough into which a pipe or tube means 23 can be fitted and held by a suitable spring retainer clip 24 as shown in FIGURE 2. This tube or pipe means 23 provides a conduit connection to an output chamber 25 visible in FIGURES 2, 3 and 5 of the drawings. This output chamber 25 communicates with a substantially annular recess 26 peripherally thereof wherein an impeller or pump blade means 27 with a central integral hub portion 28 is provided. The impeller and integral hub portion thereof can be seen in views of FIGURES 2 and 10 of the drawings and this impeller and integral hub portion can be mounted by press-fit and the like to one end of a single shaft 29 that can be seen in views of FIGURES 2, 7 and 10 of the drawings. This single shaft 29 is journaled for rotation in a single sleeve-like bearing means 30 press-fitted axially into an opening of a hub-like extension or projection 31 of the unitary body portion. The single bearing means 30 can be made of lubricant-impregnated sintered metal as well as other long-wearing metal alloy materials, and it is to be noted that substantially one-half of the length of this bearing means is press-fitted into the hub-like extension 31 of the unitary body portion 21 while a remaining half of the bearing means projects axially therefrom in a direction away from the end of the shaft where the pump impeller means is mounted. The shaft 29 can be provided with spiral grooves 32 as shown in FIGURE 7 for passage and distribution of fluid for lubricating purposes peripherally between the shaft and bearing means 30. The pump-motor means in accordance with the present invention is intended for use submerged in fuel such as gasoline and other combustible liquid materials subject to displacement from a container or storage means 33 outlined in FIGURE 2. Thus, liquid fuel in such a storage means 33 can be used directly for limited removal from chamber 26 by the spiral grooves 32 along a lower periphery of the shaft 29 which projects at one end into the chamber 26 wherein liquid fuel is available and is adapted to be centrifugally pumped into the output chamber 25 in a well-known manner. Some liquid fuel used for lubricating purposes is distributed over bearing surfacing by the spiral grooves 32 and this fuel can escape from motor space through case openings. The grooves provide only a very limited pumping action of such liquid fuel for lubricating purposes between the shaft and the bearing means 30.

The shaft 29 also carries a slotted magnetic core 34 adjacent to an end thereof remote from the end to which the pump impeller means is press-fitted. This slotted magnetic core 34 can be seen in views of FIGURES 2, 7 and 8 as well as diagrammatically in FIGURE 9. The magnetic core can be made by a stacking of a plurality of metal laminations or otherwise, and splines 35 extending longitudinally near one end of the shaft 29 can project outwardly for press-fitting of the magnetic core 34 thereon. A rotor winding means 36 can be fitted into the slots of the magnetic core 34 and can include a plurality of coils or elements electrically connected at predetermined locations to a plurality of commutator segments 37 as

diagrammatically represented in FIGURE 9. Each of the commutator segments 37 includes a relatively flat central body portion with opposite curved ends 38 forming a generally C-shaped configuration except for a projection 39 extending laterally away therefrom for connection of predetermined leads to the winding 36 as indicated particularly in FIGURE 2. Each of the commutator segments 37 is anchored by the opposite curved ends 38 to an insulating sleeve means 40, which can have saw cuts produced therein during manufacturing procedure of cutting an annular copper ring into commutator segments, which is concentrically fitted axially against the magnetic core 34 insulated from the windings 36 subsequently added thereto as shown in FIGURE 2. This insulating sleeve member 40 is further held by a covering of plastic core insulating material 41 which encapsulates the magnetic core 34 due to dipping in plastic material or coating in a fluidized bed such that an end of the covering 41 adjacent to the commutator means becomes bonded peripherally to the insulating sleeve member 40 for at least a quarter of the axial length of the member 40. The sleeve member 40 of insulating material is thus pre-positioned to be located concentrically around an intermediate portion of the shaft 29 though spaced radially outwardly therefrom for a predetermined distance to permit fitting thereof telescopically around the free or exposed end of the bearing means 30 noted earlier. This telescopic fitting of the free or exposed end of the bearing means 30 relative to the commutator means and insulating sleeve member 40 concentrically relative to the shaft 29 can be seen in FIGURE 2 and represents improvement for compactness while requiring only the single bearing means 30 for journaling of the shaft 29 that carries the pump impeller means as well as the motor rotor at opposite ends thereof. The bearing means 30, in effect, journals the shaft centrally while opposite ends of the shaft carry the rotor of the electric motor means as well as the pump impeller means as illustrated. Parts such as the base portion 121 as well as cover plate 145 and impeller 27-28 can be made from acetal resin material available commercially as known by a trade name "Delrin" thermoplastic which is a polymer of repeating $-\text{CH}_2\text{O}-$ groups.

The shaft 29 is substantially vertically located and thus the bearing means 30 provides lateral or radial support during operation of the assembly. The lower end of the shaft 29 can be provided with opposite flat portions 42 such that the impeller hub can be press-fitted thereto and an end recess 43 in the shaft receives a ball 44 of hardened metal press-fitted therein which projects axially therefrom at least in part for vertical support of the shaft directly on a metal plate 45 as can be seen in FIGURE 2. This plate 45 fits adjacent to one side of the unitary body portion 21 and closes off one side of the output chamber 25 as well as the pump or impeller chamber 26. This plate 45 has pump inlet passages 46 as indicated in FIGURES 2 and 10 and located concentrically at a predetermined diameter about axis of rotation of shaft 29 carrying the motor rotor and pump impeller means. The plate 45 also includes an outwardly extending projection 47 which complements a notch or cutout in the unitary body portion 21 such that the inlet passages 46 are necessarily properly aligned relative to axis of rotation of the shaft 29 upon installation of the plate 45 relative to the motor-pump assembly.

Mounted adjacent to the plate 45 along an underside thereof there is a fine mesh screen means 48 having a plurality of projections 49 visible in FIGURES 2 and 11 such that the screen is spaced axially away from the plate 45 and a filtering occurs as to the inlet passages 46 in the plate 45. An annular retainer 50 visible in FIGURE 2 can be press-fitted to the unitary body portion 21 thus serving to hold the plate and screen in a proper location for pump functioning. Ring means 51 of flexible, extensible insulating material can be slip-fitted

around the base portion 21 peripherally thereof as a resilient mounting including downwardly extending projections 52 visible in FIGURES 2, 12 and 13. These projections 52 provide necessary elevation of the insulating ring means 51 from a bottom of the container 33 to assure passage of the liquid fuel or gasoline and the like to an underside of the screen for inlet through the passages 46 of the pumping means driven by the electric motor and having features in accordance with the present invention. An annular metal bracket 53 slip-fitted peripherally around the ring means 51 can be provided with plural legs or outwardly extending lateral lugs 54 that support the entire motor-pump assembly and that can be suitably fastened down on the container 33 along the bottom thereof. These lugs are best seen in the view of FIGURE 1 and in the cross-sectional view of FIGURE 2.

The unitary body portion 21 includes a plurality of webs 56 integral therewith as apparent in views in FIGURES 2 and 4-6. These webs or wall-like projections extend laterally outwardly and include several cutouts or notches for differing purposes. An upper notch 57 is adapted to be engaged by an inwardly extending tang 58 struck from a cup-like downwardly extending body 59 of a cover portion 60 having a dome-like upper end providing sufficient space thereunder for rotor windings 36 carried by the magnetic core 34 on the shaft 29. A lower peripheral edge of the body 59 of the cover portion 60 can abut against the unitary body portion 21 forming a seal therewith and a lower notch 61 in the web means receives a ring-like spring means 62 held therein by a lower end or skirt or the body 59. An opposite lateral portion of the ring 62 resiliently engages a notch 63 of an arm-like insulating means 64 having a pivotal end 65 engaged into a pivotal cutout 66 between the extension 31 and integral base portion 21 as best seen in the view of FIGURE 2. An end of the arm-like insulating means 64 remote from the pivotal end 65 has a recess 67 therein adapted to receive a brush means 68, the free end of which engages commutator segments 37. The spring ring 62 urges engagement of the brush means 68 against the commutator segments 37. The brush means 68 of carbonaceous material can be fitted to the recess 67 by a press-fit and the views of FIGURES 2 and 16 provide further detailed showing thereof. It is to be noted that a conductor 70 suitably insulated from a sheath 72 can be provided such that the sheath establishes connection to one of the brush means while the conductor 70 can provide electrical connection to another of a pair of the brush means as indicated in FIGURE 16.

Further details of the cover portion 60 including the cylindrical body 59 thereof that tapers slightly outwardly can be seen in views of FIGURES 14 and 15.

Stator field means including a pair of arcuate shaped permanent magnets 71 can be press-fitted into engagement with an inner periphery of the body 59 and cover portion 60 such that a pair of diametrically oppositely located U-shaped spring metal clips 73 can urge the permanent magnets away from each other and into engagement with the body 59 and cover portion 60. The permanent magnet stator field means can be seen in views of FIGURES 2, 14 and 15. The permanent magnet stator field means 71 has a predetermined location to be radially in alignment with the rotor magnetic core 34 and windings 36 therewith. It is to be understood that auxiliary fins 76 extending in pairs in opposite directions can augment proper positioning of the body 59 and cover portion 60 relative to the unitary base portion 21 and these fins 76 can be seen in views of FIGURES 4-6 inclusive. In effect, the field or stationary portion of the motor consists of two separate pieces or one single ring of permanent magnet material disposed inside the cylindrical body 59 of metal such as steel pre-assembled to each other and then press-fitted as a cover portion onto predetermined projections on the unitary base por-

tion 21 for properly locating and retaining the motor field in proper relationship to other parts. Predetermined indentations or dimples can be provided by the webs engageable by the cylindrical body 59 to assure correct alignment of the field structure and the cover portion can be removed from the base portion by a twisting and disengagement of the tangs and interfitting parts.

In the structure illustrated by FIGURES 1 through 16 it is apparent that no separate brush rigging is required because the insulating arm-like means which support and locate the brushes are pivotally journaled by recess-like indentations 66 in the central base portion. Due to relationship of necessary parts, electrical circuitry is reduced to a minimum. Features of particular importance include use of a single bearing means to support a rotating shaft or member that carries both the rotor of a direct current motor as well as an impeller means of a pump, fan and the like. This single bearing means extends concentrically inside a commutator means so as to provide support in close proximity to the armature core of the rotor where forces of the motor are developed and must be met. The commutator is located circumferentially outside the bearing along substantially one-half thereof thereby resulting in optimum conditions of concentricity for the entire length of the commutator means. The commutator means is fastened directly to the armature core simultaneously during insulating of the rotor core. The magnetic field and motor case are a pre-assembled fitted simultaneously to the base portion and the field structure is supported and located by interlock of tangs or projections with recesses on webs or projections of the base portion. The brush holders, brush spring as well as the connections to and securing of the power supply cable to the brushes involving use of a shielded insulated conductor can result in a minimizing of electrical connections. Use of screw fasteners for the assembly can be avoided though the motor parts are secured in proper relationship while allowing for disassembly. Access to the brush means is facilitated though use of the insulating brush supports in arm-like configuration can result in increased length of service of the brushes per se. The entire assembly provides a compact though readily accessible assembly of parts without screw fasteners of any type. It is to be noted that features in accordance with the present invention can be utilized on a motor-fuel pump means disclosed with a Motor Energizing Circuit of a copending application Serial No. 70,506 filed November 18, 1960, and belonging to the assignee of the present invention.

FIGURE 17 provides a sectional view of a modified electric-fluid motor means in accordance with the present invention and generally indicated by numeral 120. A unitary base portion completely of insulating material is indicated by a numeral 121 and a bottom cover plate 145 is press-fitted thereto and held together by a metal bracket means 153. The base portion together with the cover plate 145 form an outlet chamber 125 extending tangentially outwardly from a fluid pump chamber 126 formed therebetween. An impeller blade means 127 including a central hub 128 press-fitted to a unitary shaft 129 can be provided as described earlier and this shaft 129 is centrally journaled relative to a single sleeve-like bearing means 130 press-fitted to an extension 131 of insulating material integral with the base portion 121. The bearing means 130 is press-fitted into engagement with an inner periphery of the extension 131 for at least one-half the length of the bearing means and a magnetic rotor core 134 is press-fitted to an end of a shaft 129 remote from the end to which the impeller means is press-fitted. In the illustration of FIGURE 18 it can be seen that the upper end of the sleeve-like bearing means provides a thrust support 8 for a lower side of the magnetic core 134 which carries rotor windings 136 as well as an annular insulating member 140 for commutator segments 137 having pro-

jections 139 therewith. Permanent magnet stator field means 171 can be press-fitted and held to a cylindrical body 159 of a cover portion 160 of metal such as steel in a manner similar to that described for structure of FIGURE 2. In the FIGURE 18 embodiment there is an enlarged annular lower end E of the cylindrical body 159 and cover portion 160 though the lower edge thereof fits into a groove G of the base portion of insulating material indicated by numeral 121 and webs or laterally outwardly extending projections 156 assure proper positioning of the cover portion and cylindrical body and extension E thereof.

The plate 145 can include an inlet opening 146 centrally thereof and a filter means 148 can be provided laterally thereabout. A pair of diagonally located supports 152 can be provided by the joining of the base portion 121 and cover plate 145 of insulating material. Elastomeric bushings B together with metal clips C can fit complementary to these supports 152 for maintaining proper positioning of the assembly as submerged in a tank or container for liquid fuel, gasoline and the like.

FIGURES 17, 18 and 19 illustrate a modification in brush assembly whereby a brush means 168 best seen in FIGURE 18 can be held by metal brush holder means 164 having a generally L-shaped pivot end 165 which engages an elbow-like end 195 of a metal support strip 196 one end 197 of which is held in place by a connector pin means 198 press-fitted through the unitary base portion 121 of insulating material and cover plate 145 to leave a prong end 199 thereof projecting for direct external electrical connection thereto by suitable terminal means. A substantially U-looped or modified elliptical spring means 200 straddles the elbow-like end 195 of the support strip 196 and a recess or indent 201 of the L-shaped pivot end 165 of the metal brush holder is biased radially inwardly thereby to urge engagement of the brush means 168 against the commutator segments 137. This modification of the brush assembly eliminates wiring connections thereto and provides a brush without pigtail to be held by a sheet metal stamping of suitable material such as brass, the lower end of which nests in a bend in a strip of similar material positioned and retained by the base molding of insulating material as well as a knurled connector pin 198 press-fitted thereto with a projecting prong end 199 externally accessible. A flat strip of spring material such as beryllium copper in a U-looped or elliptical configuration as indicated by reference numeral 200 is positioned into the indented portions or recesses of the L-shaped end of the brush holder and elbow-like end 195 of the support strip 196 thereby maintaining the holder in proper position relative to the supporting strip while having the spring means enhance electrical connection between the holder and strip in spite of the pivotal connection therebetween. External electrical connection to the motor portion of the assembly can be readily made to a pair of connection pins with suitable connectors. Use of the structure of FIGURES 17, 18 and 19 permits elimination of any soldering of brush pigtailed while retaining functions of the unitary base portion as described earlier.

While the embodiments of the present invention as herein disclosed constitute preferred forms, it is to be understood that other forms might be adopted.

What is claimed is as follows:

1. Structural arrangement comprising, a unitary body portion having a hub-like central projection as well as web means integral therewith, a cup-like cover portion adapted to interlock over said web means and carrying a motor stator means therein, brush means pivotally journaled outwardly from said hub-like central projection in space between said cover portion and web means, a rotor means disposed radially inwardly of said motor stator means and having a commutator axially on one side thereof toward said brush means, a mechanical load exemplified by an impeller powered during stator and

rotor energization, a common shaft extending axially to opposite sides of said unitary body portion with said mechanical load carried adjacent to one side thereof and said rotor means on an opposite side remote therefrom, and a single bearing means press-fitted into said hub-like central projection of said unitary body portion which assures maintenance of proper alignment for both said mechanical load and motor rotor-stator means.

2. The arrangement of claim 1 wherein said single bearing means has a sleeve-like configuration substantially half of which engages said unitary body portion and a remaining half of which extends about said shaft to a location concentrically within said commutator.

3. The arrangement of claim 1 wherein a screen and perforated cover plate are pressed against the mechanical load side of said unitary body portion and said mechanical load exemplified by the impeller includes a bladed member of plastic material fitted directly to an end of said shaft at a location remote from said rotor means, said bladed member providing a pumping action for transfer of liquid medium by way of inlet and outlet passages access to which occurs through a screen and perforated cover plate secured to said unitary body portion.

4. The arrangement of claim 1 wherein brush means include arm-like portions of insulating material to receive brush elements at one end and having an integral pivot projection located inwardly at an opposite end, and a wire-like spring retainer to embrace said unitary body portion and arm-like portion in assembled relationship.

5. The arrangement of claim 1 wherein said stator means includes a pair of semi-arcuate permanent magnets press-fitted to an inner periphery of said cover portion, and a pair of substantially diametrically opposite U-shaped clip means to maintain positioning of said magnets radially outside said rotor means and within said cover portion adjacent to one end thereof.

6. The arrangement of claim 1 wherein said cover portion includes a lower skirt-like end which engages said unitary body portion by tang interlock and which retains a wire-like brush spring means in position for centrally biasing said brush means against said commutator.

7. The arrangement of claim 1 wherein said brush means include a metal holder having an indented L-shaped pivot end remote from a brush-element carrying end, a metal support strip having an elbow-like end and a substantially U-looped elliptical spring means that straddles said elbow-like end of said support strip and said indented generally L-shaped pivot end of said metal brush holder biased radially inwardly thereby to urge engagement of the brush means against the commutator, said body portion being made of insulating material engageable by said metal support strip held thereto by a pin member having an externally engageable prong end projecting through said body portion for electrical connection thereto.

8. The arrangement of claim 1 wherein a screen filter is carried by said body portion for inlet opening protection, and downwardly extending mounting lugs are provided for spacing said body portion to permit fluid access to said mechanical load which is an electric fuel pump impeller.

9. Structural arrangement for an electric fuel pump assembly, comprising, a unitary body portion having a hub-like central projection with a passage therethrough as well as web means integral therewith, a cup-like cover portion adapted to interlock over said web means and carrying a motor stator means therein, brush means pivotally journaled outwardly from said hub-like central projection in space between said cover portion and web means, a rotor means disposed radially inwardly of said motor stator means and having a commutator axially on one side thereof toward said brush means, a fuel pump impeller load powered during electrical energization of said stator and rotor means, a common shaft extending

axially to opposite sides of said unitary body portion with said fuel pump impeller load carried adjacent to one side thereof and said rotor means on an opposite side remote therefrom, and a single sleeve bearing means provided peripherally in the passage through said projection such as by molding integrally as well as press-fitted therethrough, said single sleeve bearing means assuring maintenance of proper alignment for both said fuel pump impeller load and motor rotor-stator means.

10. The arrangement of claim 9 wherein a screen filter is carried by said body portion for pump inlet protection and said stator means includes a pair of semi-arcuate permanent magnets press-fitted to an inner periphery of said cover portion and resilient clip means to maintain positioning of said magnets radially outside said rotor means 15 and within said cover portion adjacent to one end thereof.
